FLUORESCENT MAINTENANCE APPARATUS

Saul Leibow, Providence, R. I.

Application October 18, 1942, Serial No. 462,217

2 Claims. (Cl. 294—20)

The invention relates to apparatus for facilitating the maintenance and repair of lighting fixtures, and has particular reference to apparatus designed for the maintenance of fluorescent lamps.

It is the principal object of the invention to provide a repair tool for readily removing and replacing fluorescent bulbs and other lamp parts.

A further object of the invention is to reduce the time and eliminate the difficulty of removal and repair of parts of fluorescent lamps which are not readily accessible to the repair man.

With the above and other objects and advantageous features in view, the invention consists of a novel arrangement of parts more fully disclosed in the detailed description following, in conjunction with the accompanying drawing, and more specifically defined in the claims appended thereto.

In the drawing,

Fig. 1 is a view, partly broken away, of the upper portion of the novel maintenance tool, with a fluorescent bulb indicated in dotted lines;

Fig. 2 is a side view of Fig. 1, with the alternative position of the tool head indicated in dotted lines;

Fig. 3 is a view, partly in section and partly broken away, of a standard type of fluorescent lamp;

Fig. 4 is a perspective, partly broken away, of a fluorescent bulb;

Fig. 5 is a side view of a standard starter arrangement;

Fig. 6 is a view similar to Fig. 5, the starter housing having a novel guideway clamped thereto;

Fig. 7 is a perspective view of the novel guideway;

Fig. 8 is a plan view of Fig. 5, the starter being removed;

Fig. 9 is a perspective of a standard starter; and

Fig. 10 is a perspective view of the novel tool part for removal and replacement of the starter, the starter being indicated in dotted lines.

It has been found desirable to facilitate the maintenance of fluorescent lamps, which are usually mounted at the ceiling or in other relatively inaccessible locations, by providing a tool with which the lamp parts may be quickly and easily removed and replaced. Such replacement is essential for proper maintenance, as a lamp which is nearing the end of its life, indicated by its flashing on and off, must be promptly re-

5 moved in order not to damage the starter and other equipment.

The present type of fluorescent lamp, however, utilizes a turn terminal or socket, and the lamp 10 is provided at each end with two pin contacts which are first inserted into a slide passage in the socket and are then turned a quarter turn to lock in the socket. Since the lamps may be of substantial length, up to at least five feet, the problem of replacement involves turning a long lamp through a quarter turn, sliding the lamp out of its sockets, and then inserting a new lamp in the reverse manner.

I have devised a novel tool which simplifies the 15 removal and the insertion of fluorescent lamps. To this end, I provide a swivel lamp grip 10, see Fig. 1, which has a base 11 of extended length, provided with two spring grip elements 12, which, as illustrated in Fig. 2, have spring fingers 13 for snapping around a lamp in gripping engagement therewith. The base 11 has a depending bracket 14, which includes two spaced arms 15, pivotally mounted on a support 16 by means of a pivot pin 17. The support 16 is recessed to seat 20 a leaf spring 18, mounted on the pin 17 and pressing against one arm 15, and a snap washer 19 is secured to the other arm 15 and cooperates with a second snap washer 20 secured to the support 16, the end of the pin 17 being threaded to receive a tightening nut 21, whereby the spring 18 is placed under pressure.

The two snap washers have their parts so arranged that the base 11 may be snapped into either one of two selective positions, either upper right, as shown in Fig. 1, or at right angles, as indicated in dotted lines in Fig. 2. The support 16 may be secured to a long pole 22 in any suitable manner, as by nails or the like, and the repair man may then reach up and snap the fingers 12 over the lamp, and then push the pole 22 up at a slight angle, whereupon the base 11 snaps around and turns the lamp 23 in its sockets 24, see Fig. 3. The contact pins 25, see Fig. 4, may now be slid out of the passages 26 in the sockets, and the lamp removed. A new lamp is replaced in the reverse manner. The described parts thus function to selectively yieldingly lock in the necessary operative positions for fluorescent lamp maintenance.

To facilitate a quick, accurate insertion of the contact pins in the passages 26, guideways 27 may be used, see Figs. 6 and 7, each guideway having clamp on arms 28 to snap over the sides of the sockets, and having flaring guide fingers 29 to guide the contact pins into the passages 26.

It may also be necessary to remove the starters 38, see Figs. 3, 8 and 9. As shown in Fig. 9, the starter has two contact pins 31 which fit in bayonet slots 32 in the sockets 24. A support 33, see Fig. 10, is provided which may be detachably secured to the other end of the pole 22 in any suitable manner, as by a bayonet slot 34 which cooperates with a nail in the pole end, the other end of the support having a plurality of spring grip fingers 35 for gripping the starters, which may then be turned for removal and for replacement.

The novel tool thus provides a simple means for removing and inserting fluorescent lamps and starters, supplemental guideways for the lamp contact pins being utilized if desired. While I have described specific constructional embodiments of the parts of the maintenance tool, it is obvious that changes in the size, shape and arrangement of the parts may be made to suit different lamp designs, without departing from the spirit and the scope of the invention as defined in the appended claims.

I claim:

1. A tool for fluorescent lamp maintenance having an elongated base, lamp gripping fingers thereon, a support, and means locking said base to said support including mechanism for selectively releasably locking said base in alignment with and at right angles to said support, said mechanism including cooperating lock washers respectively secured to the base and the support.

2. A tool for fluorescent lamp maintenance, comprising an elongated support, an elongated base extending at right angles to said support and having spaced spring finger elements adapted to snap around a lamp, and means attaching the base to one end of the support having resiliently interengaging parts for selectively snapping the base to a position in alignment with the support or to a position lateral to the support and at right angles to the first position.

SAUL LEIBOW.
